CLAIM

The ornamental design for an embossed gift bag, as shown and described.

DESCRIPTION

FIG. 1 is a perspective view of an embossed gift bag, in an open condition, showing the front and right sides and top thereof, and showing the new design;

FIG. 2 is a top plan view thereof;

FIG. 3 is a rear elevational view thereof;

FIG. 4 is a bottom plan view thereof;

FIG. 5 is a right side elevational view thereof, where the right side is a mirror image of the left side in the open condition;

FIG. 6 is a magnified view of a representative portion of the surface of the gift bag, showing an embossed image, taken at "A" of FIG. 1.

FIG. 7 is a cross sectional view of the representative portion taken at 7—7 of FIG. 6; and,

FIG. 8 is an enlarged broken-away view of another representative portion of the embossed gift bag, taken at the corner portion "B" of FIG. 3, wherein the texture in FIG. 6 is shown for ease of illustration.

The broken lines showing of flexible handles and eyelets are shown for illustrative purposes only and form no part of the claimed design. It is understood that the texture and pattern shown in detail in FIGS. 6 and 8 repeats uniformly throughout the entire exterior surface of the embossed gift bag.
